US0D1078561S

(12) **United States Design Patent** (10) **Patent No.:** **US D1,078,561 S**
(45) **Date of Patent:** **** Jun. 10, 2025**

(54) **FRONT BUMPER**

(71) Applicant: **VOLVO CAR CORPORATION**, Gothenburg (SE)

(72) Inventor: **Katharina Sachs**, Gothenburg (SE)

(73) Assignee: **VOLVO CAR CORPORATION**, Gothenburg (SE)

(**) Term: **15 Years**

(21) Appl. No.: **29/893,054**

(22) Filed: **May 24, 2023**

(30) **Foreign Application Priority Data**

Nov. 25, 2022 (EM) 015004285-0003

Nov. 25, 2022 (EM) 015004285-0007

(51) **LOC (15) Cl.** **12-16**

(52) **U.S. Cl.**

USPC **D12/169**

(58) **Field of Classification Search**

USPC D12/86, 90, 91, 92, 93, 163, 164, 166,

D12/167, 169, 196
